DESIGN FOR AN AUTOMOBILE LAMP

Frances C. Cohen, New York, N. Y., assignor to Sunshine-Radio System, Inc., New York, N. Y., a corporation of New York

Application July 13, 1936, Serial No. 63,816

Term of patent 7 years

To all whom it may concern:

Be it known that I, Frances C. Cohen, a citizen of the United States and a resident of the State of New York, in the city and county of New York, have invented a new, original, and ornamental Design for an Automobile Lamp, of which the following is a specification, reference being had to the accompanying drawing, forming part thereof.

Fig. 1 is a perspective view of an automobile lamp showing my new design.

Fig. 2 is a top plan view thereof.

The lower part of the opposite side of Fig. 1 is plain.

I claim:

The ornamental design for an automobile lamp as shown and described.

FRANCES C. COHEN.
